CLAIM

The ornamental design for a bear lamp as shown and described.

DESCRIPTION

FIG. 1 is a left perspective view of a bear lamp, showing my new design;

FIG. 2 is a right perspective view thereof;

FIG. 3 is a front elevational view thereof;

FIG. 4 is a rear elevational view thereof;

FIG. 5 is a left elevational view thereof; and,

FIG. 6 is a right elevational view thereof.

The broken lines in the figures are for the purposes of illustrating portions of the bear lamp, which form no part of the claimed design.
